US00D463981S

(12) **United States Design Patent** (10) Patent No.: **US D463,981 S**
 Crawford et al. (45) Date of Patent: ** Oct. 8, 2002

(54) **CONTAINER**

(75) Inventors: **John C. Crawford**, Mahopac, NY
 (US); **Patrick Calello**, Roseland, NJ
 (US)

(73) Assignee: **Colgate Palmolive Company**, New
 York, NY (US)

(**) Term: **14 Years**

(21) Appl. No.: **29/142,530**

(22) Filed: **May 29, 2001**

Related U.S. Application Data

(63) Continuation-in-part of application No. 29/140,161, filed on
 Apr. 12, 2001.

(51) **LOC (7) Cl. 09-01**

(52) **U.S. Cl. D9/530; D9/552**
